(57) **CLAIM**

The ornamental design for a reel and hose assembly, as shown and described.

DESCRIPTION

FIG. 1 is a left side elevational view of our new design of a reel and hose assembly.

FIG. 2 is a right side elevational view of the reel and hose assembly of FIG. 1.

FIG. 3 is a top elevational view of the reel and hose assembly of FIG. 1.

FIG. 4 is a rear elevational view of the reel and hose assembly of FIG. 1; and,

FIG. 5 is a perspective view showing the top, rear, and right side of the reel and hose assembly of FIG. 1.

The portions of a truck on which the reel and hose assembly is mounted in the figures shown in broken lines are for illustrative purposes only and form no part of the claimed design.
